UNITED STATES PATENT OFFICE.

LANSING ONDERDONK, OF NEW YORK, N. Y., ASSIGNOR TO UNION SPECIAL SEWING MACHINE COMPANY, OF CHICAGO, ILLINOIS, A CORPORATION OF ILLINOIS.

SEWING-MACHINE.

1,046,401.

Specification of Letters Patent.

Patented Dec. 3, 1912.

Application filed June 21, 1904. Serial No. 213,517.

To all whom it may concern:

Be it known that I, LANSING ONDERDONK, a citizen of the United States, residing at New York, in the county of New York, 5 State of New York, have invented certain new and useful Improvements in Sewing-Machines, of which the following is a description, reference being had to the accompanying drawing and to the letters and 10 figures of reference marked thereon.

My invention relates to an improvement in sewing machines, and especially to machines for weaving a thread back and forth upon the upper surface of the fabric, making 15 an ornamental stitch upon the upper surface of the fabric, the appearance of the stitch being similar to an embroidery stitch.

The present invention comprises as to its 20 stitch-forming mechanism, two thread-carrying needles arranged oblique to each other respecting the line of feed, with two under thread-carrying loopers coöperating therewith, to form stitches, and a vibrating thread-carrying finger above the cloth plate 25 oscillating back and forth, in a diagonal path across the line of feed to lay the thread diagonally, and so carrying its thread with respect to the needles that it passes back of the path of the needles and the thread is 30 sewed down by the needles upon the upper surface of the fabric. The finger carries preferably an ornamental cord or yarn of some kind instead of the usual thread.

The present invention relates more especially to a novel mechanism for oscillating the thread-carrying finger, and it consists in the matters hereinafter described and referred to in the appended claims.

The invention is illustrated in the accompanying drawings, in which,

Figure 1 is a front view of a portion of a sewing machine, embodying my invention; Fig. 2 is a rear view; Fig. 3 is a perspective view of my invention; Fig. 4 is a detail view 45 of the presser foot.

In these drawings, A represents the bed plate of a Union Special Machine of a usual type; B is the needle bar carrying the needles a, b, herein shown as two in number, 50 and arranged oblique to each other with respect to the line of feed, these two needles coöperate with two loopers on the under side of the throat plate.

C represents the driving shaft, provided 55 with a gear D, meshing with a gear E, upon

the front face of which is an eccentric F, embraced by the lower end of an eccentric connecting rod or pitman G, which at its upper end is pivoted to the lower end of the crank arm H, attached to the rocking shaft 60 J, journaled on the machine frame, in any suitable manner. Said shaft J has near its opposite end a downwardly depending crank arm K, which is pivotally attached at its lower end to the ball stud L, which is embraced by one end of the horizontal connecting rod M, which latter at its opposite end has a clamp embracing a ball N on the end of the stud O, which at its opposite end is fixedly sleeved upon the vertical shaft P, 70 journaled in the head of the machine, and having means at its lower end for the attachment of the shank of the thread-carrying finger Q, which oscillates back and forth across the line of feed in a diagonal path. 75

The gear F has twice the number of teeth as the lower gear, hence the finger will be driven to either one of its extreme positions, and remain there while the needles are making a full reciprocation, thus allowing the 80 needles to stitch down to the fabric the thread carried by the finger Q.

It will be seen that I have provided a thread-carrying finger which is mounted on a shaft located at one side of the line of 85 stitching, and which finger oscillates in a curved path from a point at one side of and in advance of the front needle, to a point at one side of and in rear of the back needle. By this movement of the thread finger which 90 moves once across the line of feed for each complete reciprocation of the needles, I am able to lay a thread across the line of feed between each pair of consecutive needle punctures. 95

Having thus described my invention, what I claim as new, and desire to secure by Letters Patent, is:—

1. In combination with the stitch-forming mechanism of a sewing machine, including a plurality of needles set in an oblique position with respect to the line of feed of thread laying mechanism, comprising a thread-carrying finger, a vertical shaft supporting the same, and means for operating the shaft, said vertical shaft being disposed at one side of the line of feed, whereby said thread-carrying finger moves in an arc substantially equal distances from said needles. 100
2. In combination with a driving shaft, 110

stitch forming mechanism of a sewing machine including a plurality of needles set in an oblique position with respect to the line of feed, a thread carrying finger oscillating in a curved path from a point at one side and in advance of the front needle, to a point at one side and in rear of the back needle, a vertical shaft supporting said finger, said vertical shaft being disposed at one side of the line of feed, and connections between said driving shaft and said vertical shaft, for oscillating said vertical shaft.

3. In combination with the stitch forming mechanism of a sewing machine, including a plurality of needles set in an oblique position with respect to the line of feed, a thread carrying finger, oscillating in a curved path from a point to one side and in advance of the front needle to a point to one side and in rear of the back needle, a vertical shaft supporting the same, said vertical shaft being disposed at one side of the line of feed, a rock shaft, with connections between the

rock shaft, and the shaft for oscillating the finger, a driving shaft, and connections between the driving shaft and the rock shaft for operating the latter.

4. In combination with the stitch forming mechanism of a sewing machine, including a pair of needles set in a vertical plane oblique to the line of feed, a thread carrying finger oscillating in a curved path from a point in front and to one side of the front needle to a point to one side and in rear of the back needle, a vertical shaft for supporting said finger, said vertical shaft being disposed at one side the line of feed, and means for oscillating said shaft, and a presser foot having a tongue, one side of said tongue being longer than the other.

In testimony whereof I affix my signature, in presence of two witnesses.

LANSING ONDERDONK.
